Guy Hoyt Sneddon.

UNITED STATES PATENT OFFICE.

GUY HOYT SNEDDON, OF DEL RIO, TEXAS.

DESIGN FOR A GAME-BOARD.

SPECIFICATION forming part of Design No. 27,045, dated May 11, 1897.

Application filed November 21, 1896. Serial No. 613,028. Term of patent 31 years.

To all whom it may concern:

Be it known that I, GUY HOYT SNEDDON, a citizen of the United States, residing at Del Rio, in the county of Valverde and State of Texas, have invented a new and original Design for Game-Boards, of which the following is a specification.

This invention relates to a new and original design for game-boards; and it has for its object to provide a design of this character that shall be both useful and ornamental.

The leading feature of the design resides in a game-board having a flat field on which is formed a large diamond-shaped figure, each side of which figure is formed by a pair of parallel lines having the space bounded thereby subdivided into a plurality of small square figures, an offset square figure arranged at each corner of the diamond-shaped figure, a circular figure merging into the outer corner of each offset square figure, a single circular figure formed on the field at the center of the diamond-shaped figure, a line of cross-marks extending across the field from the said single circular figure to each corner of the diamond-shaped figure, a plurality of circular figures arranged in the field beyond the diamond-shaped figure, and a plurality of broken lines extending in different directions from and between all of the circular figures.

In the drawings, Figure 1 is a plan view of a game-board embodying the herein-described design. Fig. 2 is a cross-sectional view of the board.

Referring to the drawings, the numeral 1 designates a game-board having on its upper surface a flat field 1^a, on which is formed a large diamond-shaped figure 2, each side of which figure is formed by a pair of parallel lines 3, having the space bounded thereby subdivided into a plurality of small square figures 4. At each corner of the figure 2 is arranged an offset square figure 5, and a circular figure 6 merges into the outer corner of the said offset figure 5. A single circular figure 7 is disposed centrally within the figure 2, and a line of cross-marks 8 extend from the figure 7 to each corner of the diamond-shaped figure 2. A plurality of circular figures 9 are arranged in the field beyond figure 2, and a series of broken lines 10 extend in different directions from and between all of the circular figures.

The design for the board is completed by forming oblong spaces 11 at opposite sides of figure 2 and in planes parallel with the adjacent sides of such figure.

What I claim is—

The design for a game-board herein shown and described.

In testimony that I claim the foregoing as my own I have hereto affixed my signature in the presence of two witnesses.

GUY HOYT SNEDDON.
